No. 802,063.

PATENTED OCT. 17, 1905.

G. C. WEIL.

TRANSOM OPENER.

APPLICATION FILED JAN. 28, 1905.

UNITED STATES PATENT OFFICE.

GEORGE CONRAD WEIL, OF SAN FRANCISCO, CALIFORNIA.

TRANSOM-OPENER.

No. 802,063.

Specification of Letters Patent.

Patented Oct. 17, 1905.

Application filed January 28, 1905. Serial No. 243,158.

To all whom it may concern:

Be it known that I, GEORGE CONRAD WEIL, a citizen of the United States, residing at San Francisco, in the county of San Francisco and State of California, have invented certain new and useful Improvements in Transom-Openers, of which the following is a specification.

This invention relates to a device for opening, closing, and locking transoms, the object of the invention being to provide a device of this character which shall be cheap, simple, durable and easily operated, and especially one in which the mechanism shall be all or nearly all concealed from view.

The invention resides in the novel construction, combination, and arrangement of parts for the above ends hereinafter fully specified, and particularly pointed out in the claim.

In the accompanying drawings, Figure 1 is a perspective view of a door equipped with my device, parts of the casing being broken away to show the construction. Fig. 2 is a broken perspective view of the device itself detached. Fig. 3 is a horizontal section through the shaft of the device. Fig. 4 is a horizontal section through the clamping-handle. Fig. 5 is a view similar to Fig. 4 of a modification.

Referring to the drawings, 1 represents a door, 2 the jamb therefor, and 3 the transom, hinged at its lower edge, as shown at 4. In one side of the transom-frame is secured a slotted plate 5, in which slot slides the inwardly-bent end notched at each side, as shown at 6, of a lever-arm 7, extending from the end of a horizontal shaft 8, having its bearing in the door-jamb. On the squared outer end 9 of said shaft 8 is secured the end of the other arm 10 of the lever, which extends rearwardly behind the door-casing 20, slotted as shown at 21, the outer end of which arm is pivoted

to the upper end of a long link 11, which is pivoted at its lower end to a sliding bar 12, passing through a slot 13 in a fixed plate 14 on the casing 20, said bar 12 carrying two washers 15 16, one on each side of said plate 14. Upon the threaded outer end of the bar 12 is screwed a knob 17, and when the bar has been moved up or down in the slotted plate 14 to any desired position it is locked in such position by screwing in the knob, which draws together the two washers 15 16 and clamps them upon the plate 14.

In Fig. 5 is shown a modification in which the transom is mounted upon trunnions 18, one of which extends through the door-jamb in the same manner as the shaft 8 and carries on its outer end the arm 10, operated in like manner as before.

I claim—

In combination with a transom and a door-jamb extending upward by the side of the transom, a shaft through said jamb opposite to said transom and operatively connected therewith, a slotted door-casing adjacent to said jamb, an arm extending from the end of said shaft behind said casing, a bar passing through the slot in the casing, and means connected therewith whereby it may slide vertically in said slot, a knob on the end of the bar in front of the casing, and a link connecting said arm with the end of the bar behind said casing, substantially as described.

In witness whereof I have hereunto set my hand in the presence of two subscribing witnesses.

GEORGE CONRAD WEIL.

Witnesses:

FRANCIS M. WRIGHT,
BESSIE GORFINKEL.
